UNITED STATES PATENT OFFICE.

FREDERICK H. WESTON, OF SCHENECTADY, NEW YORK, ASSIGNOR TO GENERAL ELECTRIC COMPANY, A CORPORATION OF NEW YORK.

ILLUMINATING APPARATUS.

1,159,306.

Specification of Letters Patent.

Patented Nov. 2, 1915.

Application filed December 26, 1914. Serial No. 879,052.

To all whom it may concern:

Be it known that I, FREDERICK H. WESTON, a citizen of the United States, residing at Schenectady, in the county of Schenectady, 5 State of New York, have invented certain new and useful Improvements in Illuminating Apparatus, of which the following is a specification.

My invention relates to illuminating apparatus and it is concerned with the mounting of shades, reflectors, globes, and other inclosures for light sources, and also with the mounting, support, and electrical connections of electric lamps with which the 15 shades or inclosures are used.

It is my aim to make the apparatus or devices comprising these various parts simple and rugged in construction; easy and cheap to manufacture; and secure, convenient, and 20 reliable in use.

My invention is especially advantageous in cases where one or more of the devices are to be supported by their current supply means,—as where strings of suspended 25 lamps are employed for decoration purposes, for example,—and I have accordingly described a particular construction embodying it as especially adapted and applied to this purpose; but it will be understood that 30 the utility of the invention is not confined to this application, and that it can be otherwise carried out and embodied.

In the accompanying drawing, Figure 1 is a side view of a shade mounted and supported in accordance with my invention. Fig. 2 is a view of the mounting structure on a somewhat larger scale taken at an angle of 90° from Fig. 1, certain of the parts being separated from one another. Fig. 3 is a 40 view of the mounting as seen from above, the uppermost or cover part being removed and omitted. Fig. 4 is a mid-sectional view of the lamp mounting structure without the shade. Fig. 5 is a view of the mounting as 45 seen from beneath, one of the parts being partly broken away. Fig. 6 is a mid-sectional view of the mounting structure taken 90° from Fig. 4, the cover being removed and omitted. Fig. 7 shows the interior of 50 the shade neck as seen from beneath. Fig. 8 is a fragmental sectional view illustrating the internal configuration of the shade neck in position to be applied to the mounting structure as shown above it in Fig. 2.

55 Referring, first, to Figs. 1, 2, and 3, it will

be seen that the glass shade 1 is secured to a mounting structure 2 which is in turn secured to and supported by a cable 3 preferably comprising two individually insulated stranded conductors 4, 4, arranged side by side in a common braided covering 5. The mounting structure 2 comprises a main cylindrical body 6 (preferably of porcelain, bisque, or other insulating material) which has in its upper side a trough or trench-like groove or recess 7 that receives and accommodates the cable 3 whose conductors 4, 4, form part of the current supply circuit. In the recess 7 are means for making electrical connection to the conductors 4, 4, shown as having the form of two conical ended screws 8, 9 with their points slightly blunted. These screws 8, 9 are so arranged that when the cable 3 is pressed sidewise into the recess 7 the ends of said screws will puncture the covering 5 and the insulation and be forced in among the strands of the conductors 4, 4. Ordinarily the upper side of the body 6 and the recess 7 are covered by a disk 10 of brass or other material which is secured to the body by screws 11, 11 engaged in internally threaded sleeves 12, 12 which are secured in holes in the body by their flanged, beaded, or expanded ends. (See Fig. 4). When one of the mountings 2 is to be secured and electrically connected to a cable 3, it is only necessary to place the latter over the recess 7 and the points of the screws 8, 9 and to bring the cover 10 down and force it home with the screws 11, 11 as shown in Figs. 1 and 4.

Referring, now, to Figs. 2, 4, 5 and 6, it will be seen that at the lower side of the cylindrical body 6 is a slightly tapering portion 13 of reduced diameter on which are mounted and secured socket means for holding an incandescent electric lamp and making electrical connections thereto. As shown, the socket means comprise a screw shell contact 14 and a center contact consisting of the head of a screw 15. The upper end of the shell 14 is expanded into a flange that rests against the end of said reduced portion 13 and is secured thereto by means of the conical pointed screw 8 already referred to and an additional screw 16. (See Figs. 2, 3 and 5). The screw 8 is held fast by a square nut 17 in a square recess at the bottom of the groove or recess 7, and the screw 16 is held by a similar nut 18 similarly.

arranged. (See Fig. 3.) The center contact screw 15 is held by being threaded through one end of a metal piece 19 which lies in another recess in the bottom of the groove 7, 5 and the conical pointed screw 9 is threaded through this same piece 19, its head being in a recess in the lower side of the reduced portion of the body 6. (See Figs. 5 and 6.) It will be seen, therefore, that the shell and 10 center contacts are electrically connected, respectively, to the screws 8 and 9 so as to be properly connected by the latter to the circuit conductors 4, 4.

Still referring to Figs. 2, 4, 5, and 6 it 15 will be seen that in the portion 13 of the body 6 is a transverse groove, and that in this groove a metal strip 20 is secured beneath the head of the center contact screw 15, said screw passing through the middle of 20 said strip. The strip 20 is preferably of cold-rolled sheet copper or other springy, resilient material, and the bottom of the groove containing it is preferably slanted upward both ways from the middle to allow 25 free play to the end portions of the strip. The ends of the strip 20 are bent downward a little (see Fig. 4) and their corners are slightly turned down as shown in Figs. 4 and 5. The strip 20 is of such a length that 30 both its ends project outward from the portion 13 of the body 6, so as to perform their intended function as resiliently yielding securing members for engaging the shade neck 21 internally and securing the shade 1 to the 35 mounting structure 2.

Referring, now, to Figs. 1, 7, and 8, it will be seen that the shade neck 21 is of about the same external diameter as the body 6, so as to merge with it in general outline and give the illuminating device, as a 40 whole, a good appearance. At the upper end or edge of the neck, however, the glass is turned or offset inward to form an internal shoulder 22. The opening within the 45 shoulder 22 is just a little larger than the portion 13 of the body 6, so that the latter will fit within said shoulder a little loosely. At two diametrically opposite places the shoulder 22 is interrupted and the glass wall 50 of the neck 21 carried straight up to its upper edge, the openings or notches 23 thus formed in said shoulder permitting the securing members formed by the ends of the metal strip 20 to pass. Diametrically opposite 55 site and about 90° from the notches 23 are depressions 24 in the lower surface of the shoulder 22 in which said engaging members are engaged. These various features of the shade neck can best be produced by forming 60 the upper portion of it of a reduced cross-section corresponding to the shape of the opening with the enlargements at 23, 23. The upper end of the neck can be ground off flat, and the inside can also be ground out 65 to the exact size desired. This allows the

shade, globe, or inclosure to be made by ordinary blowing methods.

It will be seen that with the relative proportions of the various parts shown, the position of the portion 13 of the body 6 in the neck 21 is determined by the abutment means or shoulder 25 at the "root" of said reduced portion against which the end of said neck abuts, and that the shade 1 is thus securely held in place in a definite position by means of the securing members of the strip 20 engaged in the depressions 24 beneath the shoulder 22. It will also be seen that under a slight force exerted to turn them with reference to the shoulder 22, said securing members will yield transversely and leave said depressions 24—the sloping edges of the depressions (see Fig. 8) and the beveled corners of said securing members facilitating this—and that in this way the shade 1 can readily be removed from the mounting 2 by merely turning it about 90°. When the bottom of the light-inclosure or shade 1 is open, any desired style of incandescent electric lamp may obviously be used with it; when it is closed, the opening of the neck 21 within the shoulder 22 is sufficient to allow a tubular lamp bulb to pass.

What I claim as new and desire to secure by Letters Patent of the United States, is:—

1. The combination with a shade neck having an inwardly extending shoulder interrupted in a plurality of places and itself having a plurality of depressions, of a lamp mounting comprising a portion fitting within said shoulder of the shade neck, means forming a shoulder against which the end of the shade neck abuts, and a plurality of resilient members projecting from said portion and engaging beneath the shoulder in the neck in the aforesaid depressions therein, said members being adapted and arranged to yield transversely and leave said depressions when said shade is turned with reference to the lamp mounting and to pass said shoulder where interrupted to permit removal of the shade from the lamp mounting.

2. A lamp and shade mounting comprising an insulating body having in its upper side a recess for the conductors of a supply circuit and having at its lower side a reduced portion adapted to fit in the neck of a shade, means in said recess for making electrical connection to the conductors extending therethrough, a cover for said recess secured to said body, socket means for holding and making electrical connections to an electric lamp secured on said reduced portion of said body and electrically connected to the aforesaid means in said recess, and means associated with said reduced portion of said body for engaging the shade neck to secure the shade to the body.

3. A lamp and shade mounting comprising

ing an insulating body having at its lower side a transversely grooved reduced portion adapted to fit in the neck of a shade, socket means for holding and making electrical connections to an electric lamp secured on said reduced portion of said body, and a metal strip secured in the groove in said reduced portion with its ends projecting so as to engage the shade neck internally and 10 secure the shade on said reduced portion.

4. A lamp and shade mounting comprising an insulating body having at its lower side a transversely grooved reduced portion adapted to fit in the neck of a shade, a screw shell mounted and secured on said reduced 15

portion, a resilient metal strip in the groove in said reduced portion with its ends projecting so as to engage the shade neck internally and secure the shade on said reduced portion, and a screw extending through said metal strip to secure it in said groove and serving as a center contact for the lamp in said screw shell. 20

In witness whereof, I have hereunto set my hand this 24th day of December 1914. 25

FREDERICK H. WESTON.
